UNITED STATES PATENT OFFICE.

STANLEY A. PHILLIPS, OF CHICAGO, ILLINOIS.

INTERNAL-COMBUSTION ENGINE.

1,131,266.

Specification of Letters Patent.

Patented Mar. 9, 1915.

Application filed November 4, 1912. Serial No. 729,372.

To all whom it may concern:

Be it known that I, STANLEY A. PHILLIPS, a resident of Chicago, in the county of Cook and State of Illinois, have invented certain new and useful Improvements in Internal-Combustion Engines, of which the following is a specification.

My invention relates to internal combustion engines and concerns particularly improved construction and arrangement in engines in which the valves are in the form of sleeves.

The failings of the ordinary puppet valve engines are well understood in the art, the action of the valves being more or less unreliable and the timing of the valves being uncertain. Frequently at high speeds the exhaust valve does not seat at all as the valve spring has not sufficient time to close the valve before the valve is again lifted to be opened. The tension of the springs of these puppet valves will vary with time and the opening and closing of the valves is further interfered with. Again, carbon will accumulate on the valve faces which are necessarily exposed to the fire of the explosions and proper seating of the valves is prevented, the result being injury to the valve faces and reduction in compression.

In order to secure the admission of a full charge of explosive gas into the cylinder it is necessary that there should be large valve opening for a long period with quick opening and cut-off. This cannot be attained in the ordinary puppet valve engines as the valve opening is at best very small, considering the volume of gas to be admitted in so short a time, usually a fraction of a second.

As a result of such small and insufficient valve openings, the cylinder will not be properly scavenged and remnants of burnt gases will mingle with the clean incoming gas. Again, puppet valves involve valve pockets or cages and broken and rough surfaces, all of which detracts from the general efficiency as is well understood, a considerable portion of the incoming gas remaining in the in-take and exhaust valve pockets where it either fails to explode or in ex-

ploding exerts no force on the piston. Furthermore, such pockets and rough surfaces cause uneven temperature distribution and other conditions, all of which detract from the general efficiency besides adding to the cost of manufacture and maintenance.

In the engine of my invention the valves

are in the form of sleeves which are positively controlled throughout their entire travel and are driven at a velocity in direct ratio to the engine speed so that no change in timing and consequent loss of power is possible. The valves are given accelerated movement and the ports are so constructed and so coöperate with the cylinder ports that the greatest possible port passageway is provided at all stages and for long periods, and with quick opening and cut-off, the arrangement being such that opening and cut-off occur when the valves are traveling at the highest speed and the valves remain open during the long period when they are traveling through the slowest portion of their paths. To accomplish this, the driving of the valves is so arranged that every point on the valve sleeve will practically describe an ellipse. My improved construction eliminates all pockets and uneven or rough surfaces and all parts can be machined to have perfectly smooth surfaces so that the resistance to gas flow is reduced to a minimum and accumulation of carbon prevented. Furthermore, elimination of such pockets and rough surfaces and varying wall thicknesses will cause much more uniform temperature distribution and wear evenly divided over the bearing surfaces. In my improved construction the valves during half of their travel on the compression and firing strokes of the engine pass over water cooled surfaces, and during the suction strokes they are cooled by the incoming fuel. This eliminates all tendency to burn out the port openings in the sleeves. Furthermore, the arrangement is such that during the compression and firing strokes, when the internal pressure is at the highest point, the sleeve travels with and in the same direction as the piston and therefore requires no more power to move it than during the other strokes.

Another important object of the invention is to provide simplified construction and arrangement for driving the sleeves and to eliminate all cams, rollers, gears, rocker arms and other unnecessary elements.

The various features of my invention will be clearly understood by referring to the accompanying drawings in which—

Figure 1 is a front elevational view with part of the cylinders and crank case in vertical diametrical section; Fig. 2 is a sectional view taken from plane 2—2 Fig. 1; Fig. 3 is a view looking from plane 3—3 Figs. 1 and

2; Fig. 4 is a group view of the lower part of the valve cylinder and some of the driving parts dissociated from one another to more clearly show the construction; Fig. 5 is a diagram showing the direction of motion of any point on the valve sleeve and designating the various cycles; Fig. 6 is a developed view of the port zone showing the relative positions of the cylinder and valve sleeve ports for one complete period of operation of the engine; and Fig. 7 is a chart showing the relative movement directions of the valve sleeve and piston and the durations of the various cycle conditions.

15 The crank shaft supporting case for the engine comprises a casting 5 from which extend supporting lugs 6 and 7. A casting 8 forms a bottom for the crank shaft chamber and is suitably secured to the main casting 5. The casting 9 forms a cover for the crank shaft housing and is integral with the cylinder structures designated as a whole 10. The crank shaft 11 is journaled at its ends in bearings 12 (only one of which is shown) whose upper and lower sections 12^a and 12^b are integral with the housing sections 5 and 8 respectively. At an intermediate point the crank shaft is supported in bearing frame 13 which is suspended from arms 14 and 15 extending diagonally downwardly from near the upper edges of the main housing section 5, as most clearly shown in Fig. 2. Interposed between the arms 14 and 15 and at the top thereof are 35 intermediate bearing sleeves 16 and 17 which assist in journaling secondary crank shafts 18 and 19 respectively. At its opposite ends shaft 18 is journaled in bearing sleeves 20 and 21 extending inwardly from 40 the opposite side walls of the crank housing section 5 while shaft 19 is journaled at its opposite ends in bearing sleeves 22 and 23 extending inwardly from the ends of the housing frame 5, the shafts being parallel 45 with the main crank shaft and at opposite sides thereof and equidistant therefrom both vertically and horizontally, as clearly shown in Fig. 2.

The main crank shaft and the secondary 50 crank shafts extend outside of the crank case at one end thereof, the main crank shaft outside of the housing carrying sprocket pinion sections 24 and 24' and the secondary shafts 18 and 19 carrying 55 sprocket wheels 25 and 26 respectively, a chain 27 connecting sprocket wheel 25 with pinion section 24 and a chain 28 connecting sprocket wheel 26 with pinion section 24' so that upon rotation of the main crank 60 shaft in one direction the secondary shafts will be driven simultaneously in the same direction, the adjustment being such that the secondary shafts travel at the same speeds but with a ratio of one to two with 65 reference to the main crank shaft. A pro-

tecting housing 29 is provided for the chain transmission, as plainly shown in Fig. 1.

Describing now the cylinder construction, each cylinder has a main inner cylindrical wall 30 and an outer wall 31 forming between them a water jacket section 32. Secured in the upper end of each cylinder is a head structure 33 comprising inner and outer walls 33^a and 33^b respectively, forming between them the water jacket section 32^a, a water supply connection 34 connecting with the water jacket section 32^a and this section communicating at *c* with the main water jacket section 32, and outlet *d* being provided at any suitable point from the lower end of the water jacket section 32. The external diameter of the head structure part extending into the cylinder is less than the internal diameter of the cylinder in order to leave an annular passageway 35 for the upper end of the sleeve valve 36, the sleeve valve fitting snugly into this passageway and the head structure being provided with an expansion band 37 and expansion rings 38. Extending through the outer and inner walls of each cylinder at opposite sides thereof and adjacent the lower edge of the head structure are the inlet and exhaust passageways or ports 39 and 40 respectively, the inner ends of these passageways being of a contour as best shown in Figs. 1 and 6. The inlet and exhaust ports coöperate respectively with inlet and exhaust ports *i* and *e* in the valve sleeve. There are preferably several inlet and exhaust ports so that there will be better distribution and the resistance to the flow of gases will be reduced to a minimum.

The pistons 41 and 42 are connected with the crank shaft 180 degrees apart in the 105 usual manner. While the pistons reciprocate the secondary shafts 18 and 19 are rotated and these shafts are so connected with the sleeve valves that any point on a sleeve valve will describe approximately an ellipse 110 during the operation of the engine. The driving connection between the secondary shafts and the sleeves is clearly shown, particularly in Figs. 3 and 4. Adjacent the lower end of each cylinder there is a connecting rod 43 having bearing frames 43^a and 43^b at its ends for journaling the opposite crank loops 18^a and 19^a of the shafts 18 and 19. The lower end of each sleeve is connected with the associated connecting 115 rod so that upon rotation of the shafts 18 and 19 the sleeve will be oscillated about its axis and will be reciprocated in the direction of its axis, each point on the sleeve describing substantially an ellipse during the 120 operation of the engine. The connection between the cylinder and its associated connecting rod is clearly shown in Figs. 3 and 4. Each sleeve has at its lower end the laterally extending lug 44. A suitable link 125

structure is pivoted to the lug 44 and to the connecting rod 43 to transmit the movements of the connecting rod to the sleeve. The link shown is in the form of a frame comprising upper and lower links 45 and 46 connected by a wall 47. The links 45 and 46 engage at opposite sides of the connecting rod 43 and are pivoted thereto by means of a pin 48 passing through the links and the bar as clearly illustrated. At their inner ends the links 45 and 46 engage at the top and bottom of the lug 44 and are pivoted thereto by a pin 49. In order to economize on space, each crank bar may have a pocket 15 43^a for receiving the lug on the associated sleeve. The various crank loops 18^a and 19^a for the various cylinders are of course angularly offset in order to get the proper sequence of operation, as is well understood in the art. In the drawings two cylinders of 20 a multiple cylinder engine are shown but it is evident that the engine may comprise any number of cylinders and the pistons and valve sleeves adjusted for the proper relative movements.

Describing now the operation, the piston in the cylinder shown in Fig. 2 and at the left of Fig. 1 is in its upper position, the various ports being all closed and the engine 30 being ready to take in gas at the next down stroke of the piston.

Referring to Fig. 6, the rows 1 to 8 show the various relative positions of the cylinder and sleeve ports during one complete operation of the engine. As has been before stated, any number of inlet or exhaust ports may be provided and as shown, three inlet and three exhaust ports are provided in the cylinder and a corresponding number of 35 ports in the sleeve, two of these sleeve ports being combined to form a double port *e i.* The first row in Fig. 6 shows all ports closed, this corresponding with the position of the piston at the head of the cylinder. As the 40 piston now starts to travel downwardly and the crank shaft turns, the connecting rods 43 will effect the rotary movement of the valve sleeve already referred to, the path traveled by the sleeve valve being indicated by the ellipses of the various rows. Intermediate relative positions of the ports during downward travel of the piston are indicated in rows 2 and 3, the sleeve valve carrying its ports to overlap with the cylinder 45 ports, the contour of these ports being such that during elliptical movement of the valve sleeve there will be the greatest possible opening at all stages of the sleeve's travel. The fourth row shows the relative positions 50 of the ports when the piston has reached the end of its down stroke and has traveled a short distance of the return stroke, and further upward movement of the piston will carry the sleeve ports farther above the cylinder ports, and the positions of the ports

when the piston reaches the upper end of its return stroke is indicated in row 5, Fig. 6, the intaken gas having been compressed during such return stroke of the piston. During the suction and compression strokes of 70 the piston, the exhaust outlets remain closed and this is indicated in rows 1 to 5. After the compression stroke, the compressed gas is ignited and during the next downward stroke there will be expansion within the 75 cylinder, and just before the end of this downward stroke is reached the sleeve ports will have been shifted downwardly and toward the left a distance as indicated in row 6. As the piston then again returns toward 80 its upper position the exhaust outlets are opened wider as indicated in row 7 and are then gradually reclosed, as indicated in row 8, and finally closed when the piston reaches the upper end of its stroke. During the 85 greater part of the compression stroke and during the expansion and exhaust strokes the inlet passageways remain closed, as indicated in rows 5, 6, 7 and 8.

In the chart shown in Fig. 7 are indicated 90 the various cycles of operation line *x* representing the travel of the piston and the line *y* representing the travel of the valve sleeve. Dotted lines 2 and 8 indicate at what particular points of the cycle are found the relative valve positions indicated in rows 2 to 8 of Fig. 6.

From the above description it is clear that the engine will operate most efficiently, the accelerated valve sleeve movement causing 100 quick opening and cut-off, and providing large port opening during the long periods when the sleeve travels slowly. A full charge of explosive gas is admitted into the cylinder, and quick and thorough exhaust is 105 therefore assured. The ports are large and of a contour that a maximum passageway is assured at all stages.

Although I have not shown any lubricating system, it is of course understood that 110 oil will be delivered to the cylinder, piston and sleeve surfaces, and it is also evident that in my construction where the valve sleeve is given an elliptical movement, the lubricant will be much more evenly distributed over the bearing surfaces and will not localize and there will be no chance for dry spots and consequent wear. Furthermore, less lubricant will be necessary as the oscillating or rotary movement of the sleeve 115 about its axis greatly facilitates its vertical movement.

As there are no puppet valves in my construction there will be no vibration and no bumping or tapping and the engine is noiseless. Furthermore, the absence of puppet valves allows a perfectly smooth and unbroken construction of cylinder wall with the result that there is much better temperature distribution and uniformity and 120 125 130

quicker cooling and the construction is greatly simplified and the cost of manufacture and maintenance greatly reduced.

I do not desire to be limited to the precise construction and arrangement shown and described as changes and modifications are possible which would still come within the scope of the invention, and I claim the following:

- 10 In an internal combustion engine, the combination with the cylinder, piston and crank shaft, of a valve sleeve concentric with said piston and cylinder, said cylinder having inlet and exhaust ports and said valve sleeve having ports, secondary shafts parallel with said crank shaft, a connecting rod having ec-
- 15

centric connection with said secondary shafts, and a link parallel with said connecting rod and pivoted to said connecting rod and said valve sleeve whereby said sleeve is given a combined oscillatory and longitudinal reciprocatory motion and said sleeve ports moved to coöperate with said cylinder ports to control the in-take and exhaust.

In witness whereof, I hereunto subscribe 25 my name this 1st day of November, A. D., 1912.

STANLEY A. PHILLIPS.
